ELECTRONIC BURNER CONTROL APPARATUS

John M. Wilson, Minneapolis, Minn., assignor to
 Minneapolis-Honeywell Regulator Company,
 Minneapolis, Minn., a corporation of Delaware

Application October 19, 1942, Serial No. 462,558

15 Claims. (Cl. 158—28)

1

The present invention is concerned with burner control apparatus and more particularly with apparatus of the type employing a thermionic amplifier.

Various burner control mechanisms employing thermionic tubes have been devised. These tubes usually rely upon the change in conductivity of a flame gap or the difference in illumination of a photoelectric cell by the burner flame to control the grid bias of the amplifier. With such thermionic amplifiers, it is undesirable to maintain the heater circuit for the amplifier energized continuously at the degree of energization which must be maintained during operation of the amplifier. Thus, it becomes necessary to increase the degree of energization of the heater circuit upon the apparatus being placed into operation. In the past, this has been accomplished by the use of switching mechanisms associated with the heater circuits. The disadvantage of such a switching mechanism is that it is very difficult to insulate it adequately from ground and often a leakage path may be established between the cathode and ground by reason of this switching mechanism in the heater circuit. Since the operation of such apparatus often requires the maintenance of a considerable potential difference between the cathode and ground, the presence of a conductive path between cathode and ground even of extremely high impedance will result in faulty operation of the apparatus.

An object of the present invention is to provide a burner control system of the type described in which the degree of energization of the heater circuit of the thermionic amplifier is changed without employing a switching mechanism associated with the heater circuit.

A further object of the present invention is to provide a burner control system of the type discussed in which the heater circuit is energized by a secondary winding of a transformer which is provided with means for normally preventing the secondary from supplying sufficient power to the heater circuit to energize the same adequately and in which means operable independently of the heater circuit is effective to increase the power output of the secondary winding.

A still further object of the present invention is to provide such an arrangement in which a magnetic shunt is provided between the primary winding of the transformer and the secondary winding connected to the heater circuit and in which means is provided for overcoming the effect of this magnetic shunt.

A still further object of the present invention is 55 power terminals and are connected by conductors

2

to provide such a burner control system in which there are two primary windings on the transformer which supplies power to the heater circuit, and in which one of these primary windings is normally energized and the other is energized only upon the burner apparatus being placed into operation.

A still further object of the present invention is to provide such an arrangement in which the 10 transformer previously referred to is provided with additional secondary windings for supplying power to a means biasing the amplifier and for supplying power to the output circuit of the amplifier, and in which the power output of all of 15 these secondary windings is normally maintained at a level inadequate for proper operation of the apparatus and is increased upon the burner apparatus being placed into operation to a proper level for normal operation of the system.

20 A still further object of the present invention is to provide such a burner control mechanism in which the transformer is provided with a further secondary winding which supplies power for the operation of the relay, the voltage existing across 25 this secondary winding being relatively constant regardless of whether the relay is energized or not.

It is a further object of the present invention to provide a circuit employing a thermionic amplifier in which the heater circuit is normally partially 30 energized, with provision for bringing the level of energization to a desired value when necessary to operate the apparatus.

A still further object of the present invention is to provide a thermionic amplifier circuit in which 35 a new and novel type of transformer is employed for supplying power to the output circuit thereof, the heater circuit thereof, and to a means for biasing the input circuit thereof, in which provision is made for changing the energization of the 40 heater circuit, the input circuit and the output circuit without the use of switching means associated with the circuit.

Other objects of the invention will be apparent from a consideration of the accompanying specification, claims and drawing in which my improved burner control apparatus is shown connected to a burner and to a main controlling thermostat to constitute a burner control system.

Referring to the specific form of the apparatus 50 shown in the drawing, the burner control device of the present invention is schematically indicated as enclosed within a housing 10. Secured to this housing 10 are various terminals 11, 12, 13, 14, 15, 16, 17, 18, and 19. The terminals 11 and 12 are

10 and 21 to line wires 22 and 23, respectively, leading to any suitable source of power (not shown). The terminals 13, 14 and 15 are thermostat terminals and are connected to a room thermostat 25. The terminals 16 and 17 are burner terminals. The terminal 18 is an ignition terminal, and the terminal 19 is a flame electrode terminal.

The thermostat 25 is of conventional construction and comprises a bimetallic element 27 to which is secured a contact blade 28. The contact blade 28 is adapted to engage fixed contacts 29 and 30. As indicated by the legends C and H adjacent the drawing, the bimetallic element 27 is secured to the contact arm 28 in such a manner that upon a drop in temperature, the contact arm 28 is moved in the direction of the fixed contacts 29 and 30. The contact arm 28 is more widely spaced from contact 30 than from contact 29. Thus, upon a drop in temperature, the contact arm 28 moves into engagement with contact 29 first and then after a predetermined further drop in temperature moves into engagement with contact 30.

The burner control apparatus is employed to control the operation of a burner generally indicated by the reference numeral 32. This burner comprises a burner nozzle 33 through which an atomized mixture of fuel and air is forced. Associated with the burner 32 is a blower driven by a motor 34. A suitable ignition means 35 is provided with the burner 32 and serves to ignite the mixture of fuel and air forced out through the burner nozzle.

The burner control mechanism of the present invention will now be described. This mechanism generally comprises an electronic discharge device 40, a transformer 41, a first relay 42, a second relay 43, and a thermal safety switch 44.

The electronic discharge device 40 is of the double triode type, having a double cathode 49 energized by a heater 50, consisting of two series connected heaters. The first triode comprises the cathode 49, a grid 52, and an anode 53. The second triode comprises the same cathode 49, a grid 55, and an anode 56. As is usual, the various elements are housed within a suitable envelope 57.

Transformer 41 is of novel design and is employed not only to supply power for the control mechanism but also to exert a controlling effect, as will be apparent from the subsequent description. This transformer comprises a core 58, consisting of a pair of side legs 60 and 61, a pair of end legs 62 and 63, and a center leg 64. Located on the end leg 62 are a primary winding 66 and a low voltage secondary winding 67. Located on the other end leg 63 is a second primary winding 69 and a further low voltage secondary winding 70. Located on the center leg 64 are a low voltage secondary winding 71 and a high voltage secondary winding 72. While the invention is not in any way limited to the particular number of turns of the various windings, in one particular embodiment of the invention it was found desirable to employ 1600 turns in windings 66 and 69, 400 turns in winding 67, 250 turns in winding 70, 300 turns in winding 71, and 4400 turns in winding 72. The primary winding 66 is permanently connected by conductors 76, 77 and 78 to terminals 11 and 12, which as previously explained, lead to line wires 22 and 23. Thus, the primary 66 is constantly energized.

The relay 42 comprises a relay coil 80 and a

5 pair of cooperating switch arms 81 and 82. The switch arms 81 and 82 are adapted to engage contacts 83 and 84. Normally the switch arms 81 and 82 are biased away from contacts 83 and 84 but upon energization of coil 80, the switch blades are moved into engagement with these contacts.

10 Relay 43 comprises a relay coil 86 and a pair of switch blades 87 and 88. Cooperating with switch blade 87 are a pair of switch contacts 89 and 90. Cooperating with switch blade 88 is a fixed contact 92. When the relay coil 86 is deenergized, the switch blades 87 and 88 are moved by any suitable biasing means such as gravity into engagement with contacts 90 and 92. Upon energization of relay coil 86, the switch blades 87 and 88 are moved out of engagement with contacts 90 and 92 and switch blade 87 is moved into engagement with contact 89. The relay coil 86, 15 as will be explained in more detail later, is connected in the plate circuit of the triode including anode 53 and cathode 49. The output current flowing through this relay coil 86 will be pulsating. Accordingly, a condenser 93 is connected in parallel with this coil to filter out the alternating component of this current so as to smooth the current flowing through coil 86.

20 The safety switch 44 may be of any suitable type. Thus, the safety switch may take the form shown in the patent to John M. Wilson 3,290,399, granted July 21, 1942. As shown schematically in the drawing for purposes of illustration, the safety switch comprises a pair of switch blades 96 and 97 which are biased apart and are held in engagement by a bimetallic element 98. Associated with the bimetallic element is an electrical heater element 99. The bimetallic element 98 is adapted to warp to the right upon being heated. Thus, upon heater 99 being energized sufficiently long, the right-hand end of the bimetallic element 98 is moved to the right so as no longer to be underneath switch blade 97. Upon this happening, switch blade 97 is free to move away from switch blade 96. Thereafter, it is necessary to manually reset the switch before the safety switch can be reclosed.

25 Reference numerals 103 and 104 designate a pair of condensers. These condensers are charged in one direction or the other, and the charge on these condensers determines to a large extent the bias of grids 52 and 55. Resistors 105 and 106 are provided and these resistors cooperate with condenser 103 to constitute a filter network.

30 Reference numerals 107, 108 and 109 are employed to designate resistors which function as protective resistances in circuits which will be referred to later.

35 A flame electrode 110 is disclosed adjacent the burner flame in series to control the biasing grid 52 in accordance with the conductivity of the gap between electrode 110 and burner 32.

Operation

40 The various elements are shown in the position which they occupy when the temperature to which thermostat 25 is exposed is at or above the desired value. The burner 32 is not in operation and the various elements of the control mechanism are in the condition which they assume when the system is shut down.

45 Under these conditions, the heater 50 associated with cathode 49 is slightly energized by reason of its connection through conductors 114 and 116 with secondary winding 70. Despite the fact that

the primary 66 is permanently energized and despite the fact that secondary 70 is constantly connected to the heater element 50, the heater is only energized partially under these conditions. This is due to the fact that the flux produced by primary winding 66 is able to flow through both center leg 64 and end leg 63. The impedance in series with windings 71 and 72 on center leg 64 is considerably higher than the impedance of heater 50. As a result, less impedance is offered to the flow of flux through leg 64 than through leg 63. As a result, the flux flowing through leg 63 is only a fraction of the flux required to maintain the voltage of secondary 70 at a value sufficient to energize heater 50 properly.

During the shut-down period, the grid 52 is maintained at a potential considerably below cathode 49 due to the charge on condensers 103 and 104. Referring to condenser 104, it is possible for current to flow through condenser 104 during each half cycle that the grid is positive with respect to cathode 49, this current flow being through a circuit as follows: from the left-hand terminals of secondary 71 through conductor 117, condenser 104, conductor 118, resistor 107, conductor 119, grid 55, cathode 49, and conductors 120, 121 and 122 back to the right-hand terminal of secondary 71. During the opposite half cycle in which the grid is negative with respect to cathode 49, current cannot flow due to the fact that the grid to cathode path is conductive only when the grid is positive with respect to the cathode. During the half cycle in which grid 55 is positive with respect to cathode 49, grid 52 is also positive with respect to cathode 49. Thus, during this half cycle, current flows through condenser 104 over the following circuit: from the left-hand terminal of secondary 71 through conductor 117, condenser 104, conductor 118, resistor 105, conductor 125, resistor 106, conductor 127, grid 52, cathode 49, and conductors 120, 121 and 122 back to the right-hand terminal of secondary 71. Thus, because of the rectifying action of the grids and cathodes of both triodes, current flows through the condenser 104 in such a direction as to cause the upper terminal of the condenser 104 to become charged negatively and the lower terminal positively. Because of the fact that the upper terminal of condenser 103 is connected to the upper terminal of condenser 104, the upper terminal of condenser 103 likewise becomes charged negatively and this negative charge on condensers 104 and 103 operates to bias grid 52 negatively. The fluctuations in the value of the charge on condenser 104 are eliminated through a filter network including the resistors 105 and 106 and the condenser 103.

Because of the limited energization of heater 56 and because of the bias placed upon grid 52, it is impossible for current to flow through the output circuit of the upper triode despite the fact that this output circuit has a limited voltage applied to it constantly through the following circuit: from the right-hand terminal of secondary 72 through conductors 129 and 130, relay coil 86, conductors 131 and 132, anode 53, cathode 49, and conductors 120, 121 and 135 to the center tap of secondary 72. The fact that no current flows through this circuit is due not only to the fact that the heater 50 is not fully energized and to the fact that the grid 52 is biased negatively but also to the division of flux between the two legs 63 and 64 so that full flux does not flow through the center leg 64 on which the secondary winding 72 is located. As a result, full voltage

is not applied to the output circuit of the triode just traced.

Let it now be assumed that the temperature to which thermostat 25 is responsive drops to a value such as to cause engagement first of contact blade 28 with contact 29 and then of contact blade 28 with contact 30. No circuit is established until the contact blade 28 engages with both contacts 29 and 30. When this happens, 10 an energizing circuit is established to relay coil 80 as follows: from the left-hand terminal of secondary 67, through conductor 137, terminal 13, conductor 138, contact 29, contact blade 28, contact 30, conductor 139, terminal 15, conductor 140, contact 90, switch blade 81, conductor 178, safety switch heater 99, conductor 142, relay coil 80, safety switch blades 96 and 97, and conductor 144 back to the right-hand terminal of secondary 67. The establishment of this circuit causes relay coil 80 to be energized with the result that switch blades 81 and 82 are moved into engagement with contacts 83 and 84. The engagement of switch blade 81 with contact 83 results in a holding circuit being established to relay coil 80 as follows: 15 from the left-hand terminal of secondary 67 through conductor 137, terminal 13, conductor 138, contact 29, contact blade 28, bimetallic element 27, conductor 146, terminal 14, conductor 147, contact 83, switch blade 81, conductor 148, safety switch heater 99, conductor 142, relay coil 80, safety switch blades 96 and 97, and conductor 144 back to the other terminal of secondary winding 67. It is to be noted that the circuit just traced is independent of contact 30. Thus, it is assured 20 that the circuit to relay coil 80 will not be interrupted until the temperature has risen sufficiently to cause disengagement of contact blade 28 from contact 29. In this way, it is assured that the relay will not chatter upon insecure engagement of contact blade 28 with contact 30, due to slight fluctuations in temperature.

The engagement of switch blade 82 with contact 84 results in a circuit being established to the oil burner motor 34 as follows: from power terminal 11 through conductor 150, switch blade 82, contact 84, conductors 151, 152 and 153, burner terminal 17, conductor 154, burner motor 34, conductor 155, burner terminal 16, and conductors 156, 157 and 158 back to the other power terminal 12. The establishment of this circuit causes the burner motor to be placed into operation with the result that a mixture of fuel and oil is forced out through the nozzle 33.

The closure of switch 82 with contact 84 also 25 results in the establishment of the following circuit to the ignition means 35: from power terminal 11 through conductor 150, switch blade 82, contact 84, conductor 151, switch blade 88, contact 82, conductor 159, ignition terminal 18, conductor 160, the ignition means 35, conductors 161 and 165, burner terminal 16, and conductors 156, 157 and 158 to the other power terminal 12. The establishment of this circuit to the ignition means assures the existence of all of the conditions necessary to the establishment of combustion if the apparatus is functioning properly.

At the same time that the burner and ignition 30 circuits are established by the closure of switch blade 82 with contact 84, a circuit is established to the second primary winding 69 as follows: from the power terminal 11, through conductor 150, switch blade 82, contact 84, conductors 151, 152 and 163, primary winding 69, and conductors 157 and 158 to the other terminal 12.

The energization of the primary winding 69, as

a result of the establishment of the circuit just traced, causes the voltage of secondaries 70, 71 and 72 to be raised to the normal values for the secondaries. Since all of the flux produced by primary 69 flows through the leg 63 on which secondary 70 is located, it will be obvious there is no opportunity for the flux generated by the primary 69 to be by-passed around secondary 70 as was the case in connection with the flux generated by primary 66. Furthermore, it is impossible for any of the flux generated by primary 66 to pass through leg 63 as was previously the case. The result is that the full output of flux of both windings 66 and 69 flows through the center leg 64 so that both windings 71 and 72 are fully energized. The heater 50 is now fully energized so as to raise the cathode 49 to the desired emitting temperature. The condenser 104 now has the normal voltage of secondary 71 applied to it so that the biasing effect of this condenser is at the value required for normal operation. The potential of secondary winding 72 is also at its normal value so that full voltage is applied to the anode circuits of both triodes.

As previously indicated, the establishment of circuits to the burner and to the ignition means resulted in all of the conditions being established that are necessary to the establishment of a burner flame. The function of the apparatus housed within the housing 10 is to detect the presence of this flame. As previously noted, the condenser 104 becomes charged in such a manner that it biases grid 52 below the cut-off potential. When flame appears, a new energizing circuit is established to the condenser 104 and also to condenser 103. Referring to condenser 104, this circuit extends from the left-hand terminal of winding 72 through conductor 169, resistor 108, resistor 109, conductor 171, terminal 19, conductor 173, flame electrode 110, burner nozzle 33 to ground at 175, ground connection 176, resistor 105, conductor 118, condenser 104, conductor 117, secondary 71, and conductors 122 and 135 to the center tap of secondary 72. It will be noted that in the circuit just traced, the condenser 104 is connected in series with the flame gap and that portion of secondary 72 between the center tap and the left-hand end of the secondary. The full voltage of the left-hand portion of secondary 72 is not applied to the flame gap, however, since secondary 71 is also included in this circuit. The voltage that is hence applied is the voltage across the left-hand portion of secondary 72 minus the voltage of secondary 71. As will be apparent from a consideration of the relative values of the various windings given in an earlier portion of the specification, the voltage of secondary 71 is relatively small as compared with that existing across the left-hand portion of secondary 72. Hence, the voltage applied to this circuit is substantially the relatively large voltage that exists across the left-hand portion of secondary 72.

In the circuit traced in the preceding paragraph, the circuit was traced from the left-hand terminal of secondary 72 through flame electrode 110 to ground and through condenser 104 in a direction opposite to which the circuit was traced in describing the biasing action of condenser 104. While a certain amount of current flows through the flame in both directions, the current flow through the flame in the direction traced is much greater than that in the opposite direction. This is due to the rectifying property of the flame. It is well established that electrons tend to flow to a greater extent in the actual direction of propaga-

tion of the flame. Hence, the conventional current flow is greater in a direction opposite to the direction of the propagation of the flame. As a result, the current flow through the flame and through condenser 104 tends to impress across the condenser a direct current potential which is opposite in polarity to that impressed as a result of the current flow through the grid circuit.

The establishment of a flame across the flame gap also results in a circuit being established to condenser 103 as follows: from the left-hand end of secondary 72 through conductor 169, resistor 108, resistor 109, conductor 171, terminal 19, conductor 173, flame electrode 110, burner 33, ground connections 175 and 176, conductor 125, condenser 103, and conductors 121 and 135 to the mid point of secondary 72. As in the case of condenser 104, this new circuit is in the opposite direction to the circuit traced in connection with the biasing operation. Since the current flow in the direction just traced through the flame is greater than in the opposite direction, the condenser 103 becomes either charged in the direction opposite to that previously considered for biasing purposes or at least to a considerably lesser extent in the same direction so that the grid potential is above the cut-off potential.

The result is that condensers 103 and 104 will no longer bias the grid 52 sufficiently negative to cause deenergization of relay coil 86. Thus, sufficient current flow takes place in the output circuit of the triode including anode 53 and cathode 49 to cause relay coil 86 to be energized with the result that switch blades 87 and 88 are moved out of engagement with contacts 90 and 92 and switch blade 87 is moved into engagement with contact 89.

The movement of switch blade 87 out of engagement with contact 90 interrupts the original energizing circuit for relay coil 80. In view of the fact, however, that the holding circuit has been previously established by the engagement of switch blade 81 with contact 83, the relay coil 80 remains energized.

The engagement of switch blade 87 with contact 89 results in a new energizing circuit to relay coil 80 as follows: from the left-hand terminal of secondary 67 through conductor 137, terminal 13, conductor 138, contact 28, contact blade 28, bimetallic element 27, conductor 146, terminal 14, conductor 147, contact 83, switch blade 81, conductors 148 and 178, switch blade 87, contact 89, conductors 179 and 142, relay coil 80, thermal switch blades 96 and 97, and conductor 144 to the other terminal of secondary 67. It is to be noted that this new circuit does not include the heater 99 and that the heater 99 is effectively shunted out by conductor 178, switch blade 87, contact 89 and conductor 179. The result is that heater 99 is substantially deenergized so that bimetallic element 98 is no longer heated. Because of the shunting of heater 99, switch blades 96 and 97 are allowed to remain in engagement to permit the system to continue in operation. In other words, since the flame has been properly established across the flame gap, it is desired that the burner remain in operation as long as the thermostat 25 is calling for heat and the flame persists.

The separation of switch blade 88 from contact 92 interrupts the circuit to the ignition means 35 previously traced. The result of such interruption is that the ignition means is now de-energized. The system illustrated in the drawing 75 is of the intermittent ignition type and in such

systems, it is customary to deenergize the ignition means as soon as flame is established.

Assuming that the flame does not go out, the system will now continue in operation until such time as the room thermostat is completely satisfied. In other words, it will remain in operation until contact blade 28 has separated from both contacts 29 and 30. When this happens, all of the circuits previously traced to relay coil 86 are interrupted with the result that switch blade 82 separates from contact 84 to cause deenergization of the oil burner and of primary winding 69. The deenergization of primary winding 69 reduces the energization of the cathode heater 50 to a value lower than that necessary to cause operation of the cathode. The deenergization of primary winding 69 also reduces the voltage applied to the output circuit of the upper triode and reduces the amount of voltage applied to the biasing means. In other words, the various voltages applied to the flame detecting apparatus are substantially reduced as soon as the oil burner motor is stopped and the charge on condenser 104 resumes a value such as to cause the relay coil 86 to be deenergized.

While the operation has been discussed in connection with the case where the heater 50 is substantially deenergized when the thermostat 25 is satisfied, it is to be understood that the energization of the heater 50 may be caused to assume any desired value. In many cases, it may be desirable to maintain heater 50 partially energized to a substantial extent when the thermostat is satisfied. The advantage of this is that the time required for the cathodes to be heated when there is a call for burner operation is relatively short. Since the only appreciable delay in the response of the apparatus to the establishment of a flame is that due to the heating of the cathode 50, any reduction in the heating time of cathode 50 reduces the time necessary for the apparatus to be placed in running position. Thus, in certain cases when it is desirable to have extremely short timing for the thermal safety switch, it is preferable to provide for a substantial partial energization of heater 50 when the thermostat 25 is satisfied. This can be accomplished either by increasing the reluctance of center leg 64 with respect to leg 63 or by making primary winding 66 relatively large as compared with primary winding 69.

Operation if flame is extinguished or is not initially established

If after normal burner operation has been established, the flame is extinguished for any reason, the path through the flame gap is interrupted so that the condensers 104 and 103 again become charged in such a manner as to bias grid 52 negatively. This results in relay coil 86 being deenergized so that switch blade 81 is moved out of engagement with contact 89 and switch blade 88 is moved into engagement with contact 92. The movement of switch blade 87 out of engagement with contact 89 breaks the shunt circuit around the safety switch heater 99. As a result, the safety switch again starts the timing cycle at the end of which the switch blades 96 and 97 are opened if combustion has not been established. The re-engagement of switch blade 88 with contact 92 re-establishes the circuit to the ignition means. If the conditions are still proper for initiating combustion, the re-energized ignition means will relight the burner and the cycle previously discussed will be repeated. If, however, the interruption of the burner flame

is due to a condition which prevents the resumption of proper burner operation without manual intervention, the safety switch 44 will operate to shut down the system at the end of a predetermined period of time.

Likewise, if flame should not be established initially upon a call for heat by the thermostat, the safety switch heater would remain energized sufficiently long to shut down the system.

Presence of other conditions than flame or normal absence of flame

The electronic apparatus of the present application is able not only to differentiate between a normal flame and a normal absence of a flame but is able to differentiate between flame conditions and various types of impedance conditions across the flame gap that might otherwise falsely indicate the presence of a flame. For example, if the apparatus were operated solely in accordance with the magnitude of the impedance across the flame gap, a short circuit condition would cause the system to operate as though a flame were present. This is extremely undesirable because it may happen that the flame electrode accidentally engages the burner. Again, it often happens that after long periods of use, carbon forms around the flame electrode until a point is reached such that the flame gap is actually bridged by the carbon. Under certain conditions, the impedance of the gap to the carbon may actually be almost identical to that of the impedance when a flame is present. Again, it is necessary to distinguish between a normal flame and such a high resistance impedance.

Consider first the situation in which, due to the accumulation of carbon or for other reasons, an impedance exists across the flame gap which is substantially the same in magnitude as the impedance of a normal flame. Under these conditions, the current flow across the flame gap and through condensers 104 and 103 will take place. However, the impedance of the flame gap is not rectifying so that the current flow is the same in both directions. It is essentially nothing more than alternating current and the potential impressed across the condenser 104 due to this current flow therethrough has no direct current component whatsoever. Thus, the direct current potential across condensers 103 and 104 is exactly the same as that due to the current flow through the grid circuit. As previously pointed out, this potential causes the grid 52 to be biased to a point where relay coil 86 is deenergized.

When a short circuit condition exists between the flame electrode and ground, it is obvious that the impedance is again a non-rectifying impedance so that the direct current potential across condensers 104 and 103 tends to be the same. However, certain other factors enter into the operation due to a decrease in impedance across the flame gap. It will be noted that as the impedance between flame gap 10 and ground becomes less and less, the grid 52 tends to be connected through a relatively low impedance path directly to the left-hand end of secondary 12, this circuit being as follows: from grid 52 through conductor 127, resistor 108, conductor 125, ground connection 176, ground connection 175, burner nozzle 33, flame electrode 110, conductor 173, terminal 19, conductor 171, resistors 109 and 108, and conductor 169 to the left-hand end of secondary 12. Since the anode 53 is connected to the right-hand end of secondary 12, the voltage impressed across

grid 52 by this connection tends to be 180 degrees out of phase with the voltage between the anode and cathode. Were it exactly 180 degrees out of phase, it would bias the grid 52 even more negatively and hence prevent the flow of current through relay coil 86. However, the condenser 104 and the flame impedance in effect form a phase shifting bridge, to one terminal of which grid 52 is connected. The cathode 49 is connected to another terminal. The result is that the increased voltage applied to the grid as a result of the decrease in impedance across the flame gap tends to be shifted in phase so that it is no longer 180 degrees out of phase with respect to the voltage applied to anode 56. Were there no complicating factors, this voltage would tend to be displaced in phase to such an extent as actually to raise the potential of grid 52. However, the effect of the triode including anode 56 and cathode 49 is present to an increasing extent as the flame gap resistance is decreased. It is to be noted that any decrease in flame gap resistance tends to connect grid 55 to a point closer in potential to that of anode 56 through a circuit including conductor 119, resistors 107 and 105, ground connections 176 and 175, burner nozzle 33, flame electrode 110, conductor 173, terminal 19, conductor 171, resistor 109 and conductor 184. Hence, the anode current of this triode is increased. This tends to produce a corrective shift in phase so as to bring the grid voltage more nearly 180 degrees out of phase with the potential applied to anode 53. Due to the cooperative action of anode 56, the triode including anode 53 and the cathode 49 remains sufficiently non-conductive so as to prevent energization of relay coil 86.

Summary

It is to be noted that in the operation traced above the transformer 41 functions not only to supply power to the flame detecting apparatus but also to reduce the amount of power supplied to various portions thereof when the thermostat is satisfied without reducing the amount of power supplied to the relay coil 80 upon a call for heat. Since the secondary 67 is mounted on the same leg as the constantly energized primary winding 66, the full amount of magneto-motive force generated by winding 66 is available for inducing a voltage in secondary 67. Because of this action of the transformer 41, it is unnecessary to have any switching connections between the various control circuits and the heater circuit. If a switch blade positioned by relay coil 80 were used to change the circuit connections of either the heater circuit, the biasing circuit, or the anode circuit, there would be a danger of a high voltage leak through such switches to ground. It is very difficult to insulate a relay blade adequately from ground where very high potentials are involved such as is employed in connection with the flame gap. Obviously, any leakage to ground at undesired points will influence the operation of the system since the proper operation of the system depends upon the existence of an impedance of the right character and magnitude between the flame electrode and ground. By utilizing the transformer itself as a switching means, this difficulty is overcome. The only switching action performed in connection with any of the windings of the transformer is in connection with primary winding 69 and the secondary winding 67. These windings are entirely separate from the windings employed for energizing the various portions of

the circuits directly associated with the electronic device 40.

While I have disclosed the use of a flame electrode for detecting the presence of a flame, a photoelectric cell could readily be substituted for the flame gap. Such a cell due to its rectifying properties, when exposed to a source of light such as a burner flame, introduces a rectifying effect similar to that of the flame itself. For this reason, wherever the expression "means exposed to a burner flame" or similar expression is employed in the appended claims, it is to be understood that this term is to be construed broadly enough as to be readable upon operation with either a photoelectric cell or a flame gap.

In one particular embodiment of my invention, it was found desirable to employ a one megohm resistor for resistor 105, a five megohm resistor for resistor 107, a two megohm resistor for element 108, a ten thousand ohm resistor for element 108, and a one megohm resistor for member 109. The condenser selected for condensers 103 and 104 each had a capacity of 0.02 microfarad. A 0.5 microfarad condenser was employed for element 93. The number of turns for the various windings of transformer 58 in this particular embodiment of the invention have already been referred to. It is to be understood that the invention is in no way limited to these particular values and that they are given merely to indicate more clearly the nature of one embodiment of the invention.

In general, while I have disclosed a specific embodiment of my invention for purposes of illustration, it is to be understood that my invention is to be limited only by the scope of the appended claims.

I claim as my invention:

1. In burner control apparatus; a relay for controlling a burner; apparatus for detecting the presence of a burner flame; said apparatus comprising a thermionic discharge device having an anode, a control element, and a cathode and heater circuit therefor for rendering said cathode electron-emissive to a predetermined degree; a transformer having a normally energized primary winding, a second normally deenergized primary winding, and at least two secondary windings; a first of said secondary windings being connected to said heater circuit; circuit connections between a second of said windings, said cathode, and said control element, said circuit connections being effective normally to bias said control element with respect to said cathode so that said discharge device is effectively non-conductive; means adapted to be exposed to a burner flame and operative to overcome the effect of said biasing connections sufficiently to make said discharge device conductive; said first and second secondary windings normally being incapable of supplying sufficient power to said heater and biasing circuits to cause them to function in the manner above recited; and means controlled by said relay effective upon the latter being energized to cause the energization of said second primary winding so as to cause the power output of both secondary windings to be increased to desired values for proper operation of said apparatus as above recited.

2. In combination, an electronic amplifier having a control electrode, a relay, a plurality of sources of alternating power, biasing means adapted to maintain said control electrode at a potential such that said amplifier is effectively non-conductive, connections between a first of

said sources of power and said biasing means, connections between a second of said sources of power and the output circuit of said amplifier, a connection between said control electrode and a point on said second source such that the connection tends to aid said biasing means, said connection including a gap adapted to be bridged by an impedance, means associated with said connection and effective when said impedance is rectifying to maintain said control electrode at a different potential such that said amplifier is effectively conductive, said sources of alternating power normally being continuously operative but insufficient in power output to energize said biasing means and said output circuit to the extent necessary for operation of said amplifier as above recited, and means controlled by said relay for increasing the power output of both sources of power to the extent necessary to cause operation of the amplifier in the manner above recited.

3. In combination, a thermionic amplifier having an anode, a control electrode, a cathode, and a heater circuit therefor for rendering said cathode electron-emissive to a predetermined degree, a relay, a plurality of sources of alternating power, connections between a first of said sources of alternating power and said heater circuit, biasing means effective normally to maintain said control electrode at a potential such that said amplifier is effectively non-conductive, connections between a second of said sources of power and said biasing means, a third of said sources of power being connected in series with the anode and cathode of said amplifier, a connection between said control electrode and a point on said second source such that the connection tends to aid said biasing means, said connection including a gap adapted to be bridged by an impedance, means associated with said connection and effective when said impedance is rectifying to maintain said control electrode at a different potential such that said amplifier is effectively conductive, said sources of alternating power normally being continuously operative but insufficient in power output to energize said heater circuit, said output circuit, and said biasing means to the extent necessary for operation of said amplifier as above recited, and means controlled by said relay for increasing the power output of all of said sources of power to the extent necessary to cause operation of the amplifier in the manner above recited.

4. In combination, a thermionic amplifier having an anode, a control electrode, a cathode, and a heater circuit therefor for rendering said cathode electron-emissive to a predetermined degree, a relay, a transformer having a normally energized primary winding and a plurality of secondary windings, one of said secondary windings being connected to said heater circuit to energize the same, biasing means adapted to maintain said control electrode at a potential such that said amplifier is effectively non-conductive, connections between a second of said secondary windings and said biasing means, connections between a third of said windings and the anode and cathode of said amplifier, a connection between said control electrode and a point on said third secondary winding such that the connection tends to aid said biasing means, said connection including a gap adapted to be bridged by an impedance, means associated with said connection and effective when said impedance is rectifying to maintain said control

electrode at a different potential such that said amplifier is effectively conductive, said first, second and third secondary windings normally supplying insufficient power to energize said heater circuit, said output circuit, and said biasing means to the extent necessary for operation of said amplifier as above recited, and means controlled by said relay operative independently of said normally energized primary winding to increase the power output of said secondary windings to the extent necessary to cause operation of the amplifier in the manner above recited.

5. In combination, a thermionic discharge device comprising a cathode and a heater circuit therefor for rendering said cathode electron-emissive to a predetermined degree, an electrically operated relay controlled by said discharge device, a transformer comprising a core, a secondary winding on said core and connected to said heater circuit to energize the same, a primary winding on said core, and a magnetic shunt between said primary and secondary windings effective to bypass part of the flux generated by said primary winding so that the power supplied to said heater circuit by said secondary winding is normally sufficient to heat said cathode to a value less than that required for said cathode to be electron-emissive to said predetermined degree such as necessary to enable said discharge device to cause operative energization of said electrically operated relay, and means for forcing further flux through said secondary winding to cause adequate energization of said heater circuit to cause the cathode to be electron-emissive to said predetermined degree.

6. In a burner control system, a burner, means for controlling the delivery of fuel to said burner, a main control device controlling said fuel controlling means, apparatus for detecting the presence of a burner flame, said apparatus comprising a thermionic discharge device having a cathode and a heater circuit therefor, energizing means normally constantly connected to said heater circuit but incapable of adequately energizing said heater circuit, and means independent of said heater circuit operable upon said control device calling for operation of said fuel controlling means to increase the power output of said energizing means to a value such that said heater circuit is adequately energized.

7. In combination; an electronic discharge device having input and output circuits; a transformer having a core comprising at least three portions one of which constitutes a magnetic shunt between the second and third portions, a first primary winding on the second portion, secondary windings on the third portion, and a second primary winding on the magnetic shunt portion; normally permanent connections between said first primary winding and a source of alternating power; normally permanent connections between said secondary windings and said input and output circuits; and means for selectively controlling the energization of said second primary winding by said alternating source of power to control the power supplied to said input and output circuits by said secondary windings.

8. In combination; an electronic discharge device having an output circuit designed for the application of a predetermined voltage thereto; a transformer having a core comprising at least three portions one of which magnetically shunts another, a first primary winding and a first secondary winding on one portion, a further sec-

ondary winding on another portion, and a second primary winding on a third portion; normally permanent connections between said first primary winding and a source of power; normally permanent connections between said secondary winding and said output circuit; relay means; a main control switch; an energizing circuit for said relay means comprising said first primary winding and said main control switch; and means controlled by said relay for energizing said second primary winding to increase the voltage supplied to said output circuit by said secondary winding to said predetermined value.

9. In a burner control system, a burner, means for controlling the delivery of fuel to said burner, a relay for controlling the operation of said fuel controlling means, a main controlling switch for controlling the energization of said relay, apparatus for detecting the presence of a burner flame, said apparatus comprising a thermionic discharge device having a cathode and a heater circuit therefor, a transformer having a secondary winding for energizing said heater circuit, said transformer being normally effective to induce in said secondary winding a voltage of such magnitude that said heater circuit is inadequately energized, and means controlled by said relay and effective upon said relay being energized upon said main controlling switch being closed to cause said transformer to increase the voltage induced in said secondary winding so that said heater circuit is energized sufficiently to heat said cathode adequately.

10. In apparatus for detecting the presence of a burner flame; a thermionic discharge device having an anode, a control element, and a cathode and heater circuit therefor for rendering said cathode electron-emissive to a predetermined degree; a transformer having a constantly energized primary and at least two secondary windings; a first of said secondary windings being constantly connected to said heater circuit; circuit connections between a second of said windings, said cathode, and said control element, said circuit connections being effective normally to bias said control element with respect to said cathode sufficiently to render said discharge device effectively non-conductive; means adapted to be exposed to a burner flame and operative to overcome the effect of said biasing connections sufficiently to make said discharge device conductive; said first and second secondary windings normally being incapable of supplying sufficient power to said heater and biasing circuits to cause them to function in the manner above recited; and means independent of said primary winding for causing said secondary windings to be subjected to an increased amount of flux so as to cause the outputs of both secondary windings to be increased simultaneously to desired values for proper operation of said apparatus as above recited.

11. In burner control apparatus; means for controlling a burner; apparatus for detecting the presence of a burner flame; said apparatus comprising a thermionic discharge device having an anode, a control element, and a cathode with a heater circuit therefor for rendering said cathode electron-emissive to a predetermined degree; a transformer having a constantly energized primary and at least two secondary windings; a first of said secondary windings being constantly connected to said heater circuit; circuit connections between a second of said windings, said cathode, and said control element, said circuit connections being effective normally to bias said control ele-

ment with respect to said cathode so that said discharge device is effectively non-conductive; means adapted to be exposed to a burner flame and operative to overcome the effect of said biasing connections sufficiently to make said discharge device conductive; said first and second secondary windings normally being incapable of supplying sufficient power to said heater and biasing circuits to cause them to function in the manner above recited; and means independent of said primary winding and controlled by said burner controlling means for causing said secondary windings to be subjected to an increased amount of flux upon said burner controlling means being

5 placed into operation to cause the outputs of both secondary windings to be increased to desired values for proper operation of said apparatus as above recited.

12. In an apparatus for detecting the presence 20 of a burner flame; said apparatus comprising a thermionic discharge device having an anode, a control element, and a cathode and heater circuit therefor for rendering said cathode electron-emissive to a predetermined degree; a transformer having a constantly energized primary and at least three secondary windings; a first of said secondary windings being constantly connected to said heater circuit; circuit connections between a second of said windings, said cathode, 30 and said control element, said circuit connections being effective normally to bias said control element with respect to said cathode so that said discharge device is effectively non-conductive; connections between a third of said secondary 35 windings, said anode, and said cathode; means adapted to be exposed to a burner flame and operative to overcome the effect of said biasing connections sufficiently to cause a current flow between said anode and said cathode as a result of the voltage applied by said third secondary winding; said secondary windings normally being incapable of supplying sufficient power to the circuit connections with which they are associated to cause them to function in the manner 40 above recited; and means independent of said primary winding and said three secondary windings for causing all three of said secondary windings to be subjected to an increased amount of flux upon said burner controlling means being 50 placed into operation to cause the outputs of all three of said secondary windings to be increased simultaneously to desired values for proper operation of said apparatus as above recited.

13. In burner control apparatus; means including a relay adapted to control the delivery of fuel to a burner, means for controlling the operation of said relay including apparatus for detecting the presence of a burner flame, said apparatus including a thermionic discharge device having 60 a cathode and a heater circuit therefor, energizing means normally constantly connected to said heater circuit but incapable of adequately energizing said heater circuit, and means independent of said heater circuit operable upon said relay being energized to increase the power output of said energizing means to a value such that said heater circuit is adequately energized.

14. In combination, detecting apparatus, said apparatus including a thermionic discharge device having an energizing heater circuit therefor, a relay controlled by said discharge device, a transformer having two primary windings and at least one secondary winding, one of said primary windings being constantly energized, said 70 75 one secondary winding being connected to said

17

heater circuit, a magnetic shunt between said primary and said one secondary winding so that said secondary winding is normally incapable of energizing said heater circuit to the extent necessary to enable said discharge device to cause operative energization of said relay, and means to complete an energizing circuit to said other primary winding to cause said secondary winding to increase the energization of said heater circuit to the extent necessary to enable said discharge device to cause operative energization of said relay.

15. In combination, detection apparatus, said apparatus comprising a thermionic discharge device having an energizing heater circuit therefor, a transformer having a constantly energized primary and two secondary windings, a first of said secondary windings being connected to said heater circuit, a main controlling switch, a control relay having an energizing circuit including said other secondary winding and said main controlling switch, a second relay controlled by said discharge device, flux controlling means forming an element of said transformer for normally decreasing the flux to which said first secondary winding is subjected so as to render said first secondary winding incapable of energizing said

18

heater circuit to the extent necessary to enable said discharge device to cause operative energization of said second relay while causing said second secondary winding to be subjected to sufficient flux to render it capable of energizing said relay, and means electrically independent of said heating circuit for affecting said flux controlling means upon energization of said control relay to increase the flux to which said first secondary winding is subjected sufficiently to enable said secondary winding to energize said heater circuit to the extent necessary to enable said discharge device to cause operative energization of said second relay.
